GASEOUS CONDUCTION APPARATUS

Charles G. Smith, Medford, Mass., assignor to
Raytheon, Inc., Cambridge, Mass., a corpora-
tion of Massachusetts

Application October 29, 1928. Serial No. 315,867

4 Claims. (Cl. 250—27.5)

My invention relates to gaseous conduction apparatus and especially to rectifiers. In my prior Patent 1,617,179, granted February 8, 1927, as well as other patents and applications, I have dis-
closed a rectifier in which an anode and a sur-
rounding cathode in a gas cooperate to rectify alter-
nating current. In an application of Bush,
Serial No. 22,988, filed April 14, 1925, assigned to the same assignee as this case, is disclosed a
modification of the rectifier of the patent referred
to. The Bush type of rectifier has an enclosing
cathode with two anodes in the enclosed region.
Such a tube when properly connected will rectify
both waves of an alternating current, thus form-
ing a full wave rectifier. Rectifiers have also been
devised in which a solid partition divides a cath-
ode region into two regions with an anode to each
region. The advantage of the Bush type of recti-
fier over this latter type is the fact that the
former starts on a much lower potential and
operates with less losses. The latter type of recti-
fier is merely two single wave rectifiers in one
envelope, whereas the former type is more than
that. When suitably connected, there is ordi-
narily twice the difference in potential across the
anodes as between each anode and cathode.
Hence on starting, the tube has the benefit of a
much higher starting potential than would ordi-
narily be the case. Furthermore, when the dis-
charge between one anode and the cathode has
been initiated, ions and electrons wander out-
side the region of discharge adjacent the other
anode and thus aid in the initiation of the dis-
charge between the other anode and cathode on
reverse cycle. With this type of construction, it
has been found, however, that due to the unre-
stricted space in which the two anodes are posi-
tioned, so many ions are produced near the in-
active electrode that an undesirably large back
current exists.

It is an object of my invention to attain the
advantages of the Bush type of rectifier without
at the same time allowing considerable back cur-
rent. Another object is to attain the above object
with simplicity of structure which will not make
the rectifier any more expensive to manufacture.

Such types of rectifiers ordinarily have the va-
por of an alkali or alkaline earth metal vapor
present in order to reduce the losses through the
tube. In the case of metals like potassium and
sodium which have a relatively low vapor pres-
sure at ordinary temperatures, it is necessary that
the source from which such vapor issues, shall
be warm in order to obtain the desired vapor pres-
sure. In each case it is customary to dispose

a metallic capsule containing the metal or com-
pounds which will liberate the metal near the
region of discharge so as to be warmed thereby.
However, it has been found that small amounts of
the metal will condense near the capsule and
cause the discharge to go to that spot. The dis-
charge will thus be continuously moving over the
surface always after concentrated amounts of
metal. This causes the region of discharge to
be objectionably close to the source of vapor and
results in an unnecessary large evolution of such
vapor.

A further object of my invention, therefore, is
to devise a rectifier having a source of alkali or
alkaline earth metal vapor within it so disposed
that it is near enough to the region of discharge
to be maintained at a desirable temperature, yet,
without causing the region of discharge to ap-
proach said source.

Referring to the drawing, Figure 1 is an eleva-
tion view of a rectifier embodying my invention.

Figure 2 is a view on line 2 of Figure 1 look-
ing upwards.

The rectifier comprises a glass envelope 1 with
a reentrant press 2 terminating in tubular mem-
bers 3. Over tubular members 3 are insulators
4 of lava or any other suitable material. These
insulators are fitted over tubular members 3 and
at their free ends have enlarged annular regions
5 cut out. Sealed in press 2 are lead wires 6 and
7, which go into a base 8, suitably cemented to
the tube, and connected to suitable prongs of the
base. Leads 7 are led through tubular members
3 and have at their ends small cylindrical anodes
9 projecting through insulators 4. Anodes 9 may
be of any suitable material such as carbon,
nickel, or tantalum, and as shown, are snugly
fitted into insulators 4 and having their free
ends beyond said insulators. It will be noted
that annular regions 5 are slightly larger than
the cross sectional area of anodes 9. These
regions 5 are of the order of the mean free path
of the gas with which the tube is filled and serve
to protect the insulators from bombardment.
Lead 6 is suitably connected to a dished member
10. This member has its edges turned down into
regions 5 so that it is maintained in place by
insulators 5. The outer edge of dished member
10 carries a cylindrical member 11. This entire
assembly may further be strengthened by two
or more wires sealed in press 2. Dished member
10 and cylindrical member 11 may be made of
any suitable metal adapted to be used as a
cathode. Preferably they are made of nickel, the
inside surfaces of which may be suitably treated

with oxides of alkaline earth metals if desired, so that electron emission may be easily obtained.

In order to prevent undesirable migration of ions from the region around one anode to that around the other anode I dispose a wire mesh 13 in such a manner that the anodes are separated from each other. This mesh may be of any suitable metal such as nickel or iron and is preferably of a fineness of around 200 spaces to the inch. This mesh may be suitably supported by being welded to dished member 10. Mesh 13 allows a sufficient number of ions to percolate through to the region in which the main discharge is to take place so that the discharge may be easily initiated. At the same time, back current is cut down so that it is negligible.

In order that anodes 9 may be as close as possible to mesh 13, without making the tube as a whole unduly small, I make the entire cathode member of oblate shape as shown in Figure 2. The losses through the tube are lower by such a construction. However, it is to be clearly understood that this shape of cathode is not necessary and a round cathode of usual design may be used if desired.

The top of the cathode carries a screen 12 which may be of the same material as 13. Above this screen is a dome or cap member 30 carrying a capsule 14. The cathode is thus entirely enclosed.

The tube is exhausted and freed of occluded gases as usual and thereafter filled with one or more of the rare gases to a pressure of about 6-8 mm. Preferably helium is used. Thereafter the tube is sealed. Capsule 14 is bombarded causing the chemicals within it to be heated so that interaction occurs. The vapor of alkali or alkaline earth metal is released therefrom through minute holes or suitable openings and settles down through screen 12 on the inner surface of the cathode. The metal used is preferably potassium.

During the operating of the tube, the heat of the discharge is sufficient to warm up the region adjacent to capsule 14 so that a sufficiently great vapor pressure of alkali metal is maintained. The dome or cap 30 completely covers the top of the cathode and prevents escape of vapor discharge. Screen 12 prevents the discharge from enlarging and approaching too close to capsule 14.

While I have shown only two anodes, it is obvious that my invention is applicable to tubes containing a greater number of anodes. Between adjacent anodes, there will preferably be a mesh similar to that shown and acting in the same manner. Thus it will be seen I have devised a tube in which a plurality of anodes may operate in a communicating space with all attendant advantages without at the same time having the disadvantage of a large back current. Furthermore, I have also devised a tube in which suitable vapor to reduce the potential drop may be introduced within the discharge region without enlarging the region of discharge beyond set limits.

I claim:

1. A unidirectional space current device comprising a hermetically sealed vessel containing a relatively small-area anode, a relatively large-

area cathode, enclosure means providing in conjunction with said cathode and anode an enclosure around the space between said cathode and said anode and segregating it from the space bordering the walls of said vessel, a source of ionizable gas in said enclosure for sustaining a space discharge between said cathode and said anode, and a screen in said enclosure for segregating and holding away the discharge from said source, while permitting gas from said source to enter the discharge space. 80 85

2. A unidirectional space current device comprising a hermetically sealed vessel containing a relatively small-area anode, a hollow cathode of relatively large interior electrode area enclosing the space around said anode and segregating it from the space bordering the walls of said vessel, a conducting vaporizable body carried by said cathode in the interior thereof for supplying a vapor adapted to sustain a discharge between said cathode and said anode, and a screen in said hollow cathode for segregating and holding away the discharge from said vaporizable body, while permitting the vapors from said body to enter the discharge space. 90 95

3. A unidirectional space current device comprising a hermetically sealed vessel containing a hollow conducting member having partition means subdividing the hollow space into a plurality of compartments having each a large-area interior cathode surface, small-area anodes enclosed in said compartments to maintain unidirectional discharges with said cathode surfaces, said hollow conducting member segregating the space within its interior from the space bordering the walls of said vessel, a conducting vaporizable body carried by said hollow member in the interior thereof for supplying a vapor to said compartments adapted to sustain discharges between said anodes and said cathode surfaces, and a screen in said hollow member for segregating and holding away the discharge from said vaporizable body while permitting the vapors from said body to enter the discharge spaces in said compartments. 100 105 110

4. A unidirectional space current device comprising a hermetically sealed vessel containing a hollow conducting member having partition means subdividing the hollow space into a plurality of compartments having each a large-area interior cathode surface, small-area anodes enclosed in said compartments to maintain unidirectional discharges with said cathode surfaces, said hollow conducting member segregating the space within its interior from the space bordering the walls of said vessel, a conducting vaporizable body carried by said hollow member in the interior thereof for supplying a vapor to said compartments adapted to sustain discharges between said anodes and said cathode surfaces, and a screen in said hollow member for segregating and holding away the discharge from said vaporizable body while permitting the vapors from said body to enter the discharge space, the partition means between said compartments having openings of a size preventing the discharge in one compartment from extending into the adjacent compartment while securing ionizing action of the anode in one compartment on the content of the other compartment. 115 120 125 130 135 140 145

CHARLES G. SMITH.
